ANCHOR FOR GRATINGS

Filed March 3, 1944

INVENTOR.

Walter A. Bates.

BY

Wilkinson, Hufley, Byrnes, Wright
Otto

15 is the washer 23 having a portion 24 adapted to be turned up against a flat portion of the head 21. Said head 21 is illustrated as being of hexagonal contour, this being a convenient shape for providing a flat side portion for cooperation with the turned up portion 24. The lower extremity of the bolt 20 is provided with the nut 25 which is located within the channel of the leg 17. Said channel receives said nut 25 with sufficient closeness so that turning of said nut in said channel is prevented. The lower extremity of the bolt 20 may be upset (as indicated by the numeral 26) after said bolt and nut 25 have been assembled in the anchor 15.

The outer extremity of the leg 16 is swedged to provide a middle portion 27 and two tips 28 and 29. During the swedging operation the middle portion 27 will be raised slightly above the adjacent bottom of the channel forming the leg 16 to provide more or less rounded shoulders 30-30 adapted to abut against the lugs 14-14.

The material of the anchor 15 is bendable, and either or both of the tips 28 or 29, each having been severed from the mid portion 27 in the swedging operation, may be bent down over one or both of the lugs 14-14 to hold the anchor against movement toward the left as the parts are viewed in Figures 1, 2 and 5.

Figures 6 and 7 illustrate a modification in the form of a lug for cooperation with the anchor 15. As shown in said figures the lower portion of each of the two adjacent main bars 10-10 is severed along one plane, indicated by the section line 7-7 in Figure 6, the adjacent metal being swedged to form an angularly projecting lug 31 adapted to form an abutment functioning similarly to the corresponding abutment 14 illustrated in Figures 1 to 5.

Figures 8 and 9 illustrate another modification, in which the lower edges of the two adjacent main bars 10 have portions swedged toward each other in the form of bulges, as indicated by the numeral 32. Said bulges 32 operate as lugs similarly to the functions of the lugs 14-14 illustrated in Figures 1 to 5 and the lug 31 illustrated in Figures 6 and 7.

In practice the dimensions of the horizontally projecting portion of the angle member 13 will vary. However, the anchor 15 will be sufficiently bendable and the length of the bolt 20 will be such as to accommodate the variations in the dimensions of the angle member 13 that are encountered in practice. Furthermore, by reason of the slots 18 and 19 in the legs 16 and 17 the bolt 20 may be moved back and forth. The bolt 20, washer 23 and nut 25 will be mounted in assembled relationship with the legs 16 and 17 and the extremity of the bolt 20 will be upset, preferably at the factory. At this time the edge portion of the washer 20 will be flat and both tips 28 and 29 will extend in generally parallel relationship with the mid portion 27 of the swedged end of the leg 16.

In mounting the anchors, the workman will be located above the top of the grating. The bolt 20 will be loosened to a sufficient extent so that the two legs of the anchor can slip easily, one leg under the projecting flange of the anchor member 13, the other leg slipping over the lugs 14. Said lugs will have been swedged out at the factory at regions adjacent to the adjacent edge of the grating. The workman will hold up the anchor with a short length of wire, a piece of string, or the like, and will locate the anchor with respect to the lugs 14-14, so that the tips

extend a short distance, say about a quarter of an inch, beyond the lugs 14-14, the shoulders 30-30 being useful for this purpose. The workman will then tighten up the bolt 20, using a screw driver or the like for this purpose. The workman will bend one or both of the tips 28-29 over one or both of the lugs 14. Inasmuch as the material of the anchor is relatively soft, the workman can easily bend one or both of the tips 28 or 29 without danger of pushing the anchor away from the lugs. After the bolt 20 has been tightened to the desired degree, the edge portion 24 of the washer will be turned up against a flat face of the head 21 of said bolt 20, whereby to prevent accidental turning of said bolt.

The anchor 15, being channel-shaped in cross section, will have requisite strength without sacrificing the factor of ready bendability of the tips 28, 29.

As indicated above, in gratings as commonly sold in this country the minimum spacing between main bars is about three-fourths of an inch or a little less. The maximum spacing may be in the neighborhood of one inch. It is not necessary to stock more than one size of anchor to cover these differences in spacing between the main bars. In other words, an anchor having a maximum width of a little less than three-fourths of an inch will serve for the limits of spacing referred to. The angularity of the swedged in lugs 14-14 or the swedged in lugs 31-31 or the swedged in lugs 32-32 will insure the symmetrical spacing of the anchors between the main bars.

By reason of the fact that one or both of the tips 28 or 29 is turned down over a lug of a main bar, there is no danger that the anchor will drop off into the region below the grating. Therefore, even if the bolt 20 should become loose there is no danger that the anchor would be lost.

Though a preferred embodiment of the present invention has been described in detail, many modifications will occur to those skilled in the art. It is intended to cover all such modifications that fall within the scope of the appended claims.

What is claimed is:

1. A grating having parallel main bars and cross bars secured together, adjacent main bars having lugs swedged therefrom at regions adjacent to the bottoms thereof and spaced from said cross bars, said lugs being presented toward each other and providing upper surfaces sloping downwardly to the region between said bars.

2. A grating having parallel main bars and cross bars secured together, adjacent main bars having lugs swedged therefrom at regions adjacent to the bottoms thereof and spaced from said cross bars, said lugs being presented toward each other and providing upper surfaces sloping downwardly to the region between said bars, the angle of slope of said surfaces to the horizontal being approximately thirty degrees.

3. An anchor for securing a grating to a support comprising a U-shaped member of channel conformation providing two legs, one of said legs having a bendable tip, a bolt extending through said legs, the head of said bolt having a non-round portion, a washer underlying said head and being non-turnable with reference to said anchor, said head and said washer being disposed within the channel conformation of one of said legs, and a nut located in the channel conformation of the other of said legs, said nut being non-turnable with respect to said other leg, said

washer having a portion adapted to be turned up against the flat portion of said head to prevent relative rotation therebetween.

4. An anchor for securing a grating to a support comprising a U-shaped member of channel conformation providing two legs, one of said legs having a bendable tip, a bolt extending through said legs, the head of said bolt having a non-round portion, a washer underlying said head and being non-rotatable with respect to said anchor, said head and said washer being disposed within the channel conformation of one of said legs, and a nut located in the channel conformation of the other of said legs, said nut being non-rotatable with respect to said other leg, said washer having a portion adapted to be turned up against the flat portion of said head to prevent relative rotation therebetween, the end of said bolt being upset whereby to prevent it from becoming disengaged from said nut.

5. In combination, a grating having parallel main bars secured together, adjacent bars having lugs swedged therefrom presented toward each other, a support for said grating located under an edge portion thereof, and a U-shaped clamp embracing said support and said lugs.

6. In combination, a grating having parallel main bars secured together, adjacent bars having lugs swedged therefrom presented toward each other, a support for said grating located under an edge portion thereof, a U-shaped clamp embracing said support and said lugs, a bolt extending through the legs of said U-shaped clamp, and a nut on said bolt for holding said clamp in clamping position.

7. In combination, a grating having parallel main bars secured together, adjacent bars having lugs swedged therefrom presented toward each other, a support for said grating located under an edge portion thereof, a U-shaped clamp embracing said support and said lugs, a bolt extending through the legs of said U-shaped clamp, a nut on said bolt for holding said clamp in clamping position, and a washer underlying the head of said bolt, said washer being non-rotatably mounted with respect to said clamp and adapted to have a portion thereof turned up to prevent relative rotation between said bolt and said washer.

8. In an anchor, in combination, a U-shaped clamping member of channel conformation, one of the legs of said U-shaped member having a bendable tip at its extremity, a bolt extending through the legs of said U-shaped member, a washer underlying the head of said bolt and being non-rotatable with respect to said anchor, said washer having a portion adapted to be turned up against the head of said bolt to prevent relative rotation between said washer and said bolt, and a nut located in the channel conformation of one of the legs of said U-shaped member, said nut being non-rotatable with respect to said U-shaped member, the head of said bolt having a screw driver slot therein.

9. In an anchor, in combination, a U-shaped clamping member of channel conformation, one of

the legs of said U-shaped member having a bendable tip at its extremity, a bolt extending through the legs of said U-shaped member, a washer underlying the head of said bolt and being non-rotatable with respect to said anchor, said washer having a portion adapted to be turned up against the head of said bolt to prevent relative rotation between said washer and said bolt, and a nut located in the channel conformation of one of the legs of said U-shaped member, said nut being non-rotatable with respect to said U-shaped member, the head of said bolt having a screw driver slot therein, the end of said bolt being upset whereby to prevent it from becoming disengaged from said nut.

10. In combination, a grating having parallel main bars secured together, adjacent bars having lugs swedged therefrom presented toward each other, a support for said grating located under an edge portion thereof, and a U-shaped clamp embracing said support and said lugs, said clamp having a bendable tip adapted to be bent down over one of said lugs.

11. In combination, a grating having parallel main bars secured together, adjacent bars having lugs swedged therefrom presented toward each other, a support for said grating located under an edge portion thereof, and a U-shaped clamp embracing said support and said lugs, said clamp having a bendable tip adapted to be bent down over one of said lugs, said clamp adjacent to said tip being provided with a shouldered portion adapted to abut against said lugs for locating said clamp relative to said lugs.

12. In combination, a grating having parallel main bars secured together, adjacent bars having lugs swedged therefrom presented toward each other, a support for said grating located under an edge portion thereof, a U-shaped clamp embracing said support and said lugs, said clamp having a bendable tip adapted to be bent down over one of said lugs, a bolt extending through the legs of said U-shaped clamp, and a nut on said bolt for holding said clamp in clamping position, said nut being non-rotatable with respect to said clamp.

13. In combination, a grating having parallel main bars secured together, adjacent bars having lugs swedged therefrom presented toward each other, a support for said grating located under an edge portion thereof, a U-shaped clamp embracing said support and said lugs, said clamp having a bendable tip adapted to be bent down over one of said lugs, a bolt extending through the legs of said U-shaped clamp, a nut on said bolt for holding said clamp in clamping position, said nut being non-rotatable with respect to said clamp, and a washer underlying the head of said bolt, said head having a flat side portion, said washer being non-rotatably mounted with respect to said clamp and adapted to have a portion thereof turned up against said flat side portion to prevent relative rotation between said bolt and said washer.
